UNITED STATES PATENT OFFICE.

ROBERT S. GRAHAM AND WILLIAM B. SAVELL, OF NEWARK, NEW JERSEY.

DESIGN FOR A KEY-TOP.

SPECIFICATION forming part of Design No. 23,198, dated April 17, 1894.

Application filed March 14, 1894. Serial No. 503,644. Term of patent 14 years.

To all whom it may concern:

Be it known that we, ROBERT S. GRAHAM and WILLIAM B. SAVELL, of Newark, in the State of New Jersey, have invented and produced a new and original Design for Rubber Key-Tops, of which the following is a specification, reference being had to the accompanying drawings, forming part thereof.

Figure 1 is a sectional view of a key-top showing our design. Fig. 2 is a side elevation of the same. Fig. 3 is an inverted plan view; these three views being deemed necessary to fully illustrate our design.

Our invention relates to rubber key tops, and it consists of the design substantially as herein shown and described.

a is the body of the key-top which is circular or approximately so in its general contour

but has depending from it a circular or approximately circular downwardly and inwardly projecting flange *b*, as represented. This flange joins the body *a* substantially at its periphery, presenting in side view, exteriorly, substantially the effect of or approximating a cylinder, as shown in Fig. 2; but presenting in inverted plan view, a bottom opening of substantially smaller diameter than the periphery of the top, as shown in Fig. 3.

We claim—

The design for a key-top, substantially as shown and described.

ROBERT S. GRAHAM.
WILLIAM B. SAVELL.
